ATTORNEY

UNITED STATES PATENT OFFICE.

GEORGE W. RIST, OF HAVRE, MONTANA.

BOILER.

1,241,884.

Specification of Letters Patent.

Patented Oct. 2, 1917.

Application filed November 8, 1916. Serial No. 130,193.

To all whom it may concern:

Be it known that I, GEORGE W. RIST, a citizen of the United States, residing at Havre, in the county of Hill and State of Montana, have invented certain new and useful Improvements in Boilers, of which the following is a specification.

This invention relates to boilers, and more particularly to a boiler adapted to be used in connection with marine engines, and for similar purposes, where it is essential to reduce the loss of heat by radiation to a minimum.

One of the main objects of the invention is to provide a boiler of the character stated of simple construction and operation in which the boiler proper is surrounded by a heat insulating medium which serves to effectually prevent loss of heat by radiation. A further object is to provide a boiler and a casing in spaced relation thereto in combination with a common supporting means for the casing and boiler. A further object is to provide a boiler and a casing so constructed as to permit ready access to the boiler for inspection, repairs and similar purposes. Further objects will appear from the detailed description.

In the drawings: Figure 1 is a central longitudinal vertical section through a boiler constructed in accordance with my invention.

Fig. 2 is a section through the outer casing on line 2-2 of Fig. 1. The boiler A consists of a plurality of telescopedically connected cylindrical sections 1, 2 and 3. At each end of this boiler is secured a supporting ring 4 which is of rectangular or approximately L shape in cross section, being provided with an integral inwardly directed flange 5 which is riveted to the end section of the boiler A. Intermediate the rings 4 are mounted two spaced rings 6 and 7. The ring 6 is provided, at its inner edge, with an integral flange disposed at a right angle to the body of the ring 8. This flange 8 extends between the inner end portion of the boiler section 1 and the outer end portion of the boiler section 2, the flange 8 and the end portions of these boiler sections being riveted tightly together so as to form a continuous fluid tight closure. The ring 7 is similarly secured between the outer end portions of the boiler sections and the inner end portion of the boiler section 3. The vertical flange

of the ring 6 extends between the outwardly directed flanges 9 and 10 of the two cylindrical sections 11 and 12 of the cylindrical casing B. The flanges 9 and 10 of the sections of the casing, and the vertical flange of ring 6, are all secured tightly together by means of suitably spaced securing bolts 13 passed through the same. Suitable packing rings or gaskets 14 are placed between the flanges 9 and 10 and the lateral faces of the vertical arm of ring 6 thus insuring a fluid tight joint between these elements. The vertical arm of the ring 7 is similarly secured between the flanges 15 and 16 of the sections 12 and 17 of casing B, by means of the bolts 18. The outer end flange 19 of casing section 17 is secured to the vertical flange of the end ring 4 by means of suitably spaced bolts 20, a packing ring or gasket 21 being interposed between these two flanges so as to form a fluid tight joint. The vertical flange of the front ring 4 is similarly secured to the flange 22 of the casing section 11, by means of suitably spaced bolts 23. By this means the boiler A is mounted within the casing B in spaced relation thereto, and a fluid tight closure is effected at all joints, for the purposes to be later disclosed.

The section 17 of casing B is provided with an integral boss 24 having a central threaded aperture which receives a nipple 25. This nipple is connected by an elbow 26 to a pipe 27. By connecting the pipe 27 to a suitable exhaust pump the air in the space between the casing B and the boiler A may be exhausted so as to form a vacuum about the boiler. For this purpose the vertical flanges of the supporting rings are each provided with a plurality of suitably spaced apertures 28. To prevent collapse of the casing B a plurality of suitably spaced radially disposed reinforcing members or blocks 29 are interposed between the boiler A and the casing. These blocks act to support the casing intermediate the rings thus sufficiently reinforcing the same to prevent its collapse when the air within the casing is exhausted, and are made of asbestos, magnesia, or other heat-insulating material.

As is well known, a vacuum is one of the best of heat insulators. By surrounding the boiler A with a vacuum the loss of heat from the boiler by radiation is reduced to a minimum, thus effecting a material saving

in the cost of fuel consumed to produce a given amount of power, and producing a boiler of simple construction and high efficiency. When it is desired to repair the 5 boiler, the casing B may be removed by the simple expedient of removing the securing bolts which secure the sections of the casing to the supporting rings. This provides simple means whereby the boiler may be 10 quickly and easily inspected or repaired.

The casing B is further provided with an integral boss 30. A nipple 31 is threaded into this boss and communicates with an outwardly opening escape valve 32. This 15 valve is provided to prevent explosion of the casing B in the event of the boiler springing a leak. In this case the steam which would ordinarily collect within the casing B so as to cause explosion of the 20 same will act to open the valve 32 and escape through the same into the atmosphere. In this manner the valve acts as a safety device and also as a visual signal or indicator to give warning of a leak in the boiler A.

25 As is clearly shown in Fig. 2 of the drawings, each of the sections of the boiler casing is formed of two members of semi-cylindrical shape, each of these members being provided at its edge with an integral outwardly directed longitudinally extending 30 flange. The flanges of the upper one of these members fit on the flanges of the lower member, the two members being then detachably secured together by bolts passed 35 through aligned apertures in the flanges, suitable securing nuts being threaded on these bolts. To insure a fluid tight closure between the members of each section, a suitable packing member is interposed between 40 the securing flanges, as shown, this packing member corresponding to the gaskets secured between the flanges at the ends of the sections of the casing and the supporting rings. By this construction, the casing can

be quickly and easily disassembled for inspection or repair of the boiler.

What I claim is:

1. The combination of a boiler composed of a plurality of telescopically connected sections, a plurality of rings of approximately L-shape in cross section certain of said rings having their inner arms secured between the overlapping end portions of adjacent sections of the boiler, and certain other of said rings having their inner arms 50 secured to the end sections of the boiler, and a casing mounted about the boiler in spaced relation thereto composed of a plurality of sections, each of said sections being provided at each end with an outwardly 55 directed integral flange, said flanges being secured to the vertical arms of the said rings.

2. The combination of a boiler composed of a plurality of telescopically connected 60 sections, a plurality of rings mounted about the boiler concentric therewith, said rings being of approximately L-shape in cross section, and certain of said rings having their inner arms secured between the overlapping 65 ends of adjacent sections of the boiler, certain others of said rings having their inner arms secured to the end sections of the boiler, a casing composed of a plurality of sections mounted about the boiler in spaced 70 relation thereto, each of said sections being provided at each end with an outwardly directed integral flange and means for detachably securing the sections of the casing to the vertical arms of the said supporting 75 rings.

In testimony whereof I affix my signature in presence of two witnesses.

GEORGE W. RIST.
